UNITED STATES PATENT OFFICE.

LORENZ LEIRER, OF BUDA-PESTH, AUSTRIA-HUNGARY.

AXLE-BOX.

SPECIFICATION forming part of Letters Patent No. 332,809, dated December 22, 1885.

Application filed June 12, 1885. Serial No. 168,466. (No model.) Patented in Belgium May 20, 1885, No. 68,936, and in England May 20, 1885, No. 6,191.

To all whom it may concern:

Be it known that I, LORENZ LEIRER, a subject of the Emperor of Austria-Hungary, residing at Buda-Pesth, Austria, Hungary, have 5 invented a new and useful Improvement in Axle-Boxes and Rotating Axles, of which the following is a specification.

This invention relates to axle-boxes and rotating axles for vehicles, whereby an easy and 10 noiseless motion of the vehicles is obtained; and the invention consists of an improved construction of axle-boxes and rotating axles, as will be fully described hereinafter, and finally be pointed out in the claims.

15 In the accompanying drawings, Figures 1 and 2 represent side elevations, respectively, of the upper and lower parts of my improved axle-box for vehicles. Figs. 3 and 4 are respectively a bottom view of the upper part of 20 the axle-box and a top view of the lower part of the axle-box. Figs. 5, 6, and 7 are details of the parts forming my improved rotating axle for vehicles, and Fig. 8 is a plan of the axle.

25 In the drawings, A and B represent, respectively, the upper and lower sections of my improved box for vehicle-axles. The axle-box A B has a journal-bearing, a, at the center of which is arranged an annular groove, b, as 30 shown in Figs. 3 and 4. The groove b serves as a space for the lubricating material, which is introduced through an opening, b', in the upper part, A, and supplied from a box, c, having a hinged lid closed by a spring, c'.

35 The box, c, for the lubricating material can be made of any suitable shape and construction, and may be located at any suitable part of the axle-box A B. The front and rear faces of the axle-box are provided with ring-shaped recesses d d', that serve as dust-guards for the 40 journal. These recesses d d' inclose the axle in such a manner that a nearly-continuous surface is obtained. The lower part, B, of the axle-box fits by lugs e e' into corresponding 45 sockets, f f' of the upper part, A, by which a reliable connection of the parts is obtained. The axle-box is attached to the body of the vehicle in any suitable manner—as, for instance, by straps, screws, or other devices.

50 The axle rotates in the axle-box A B, and is made of two sections, k k', that are connected

at the center by a coupling, g, as shown in Fig. 8. The axle-sections k k' are provided at the journals h h' with annular collars i i', which fit into the annular grooves b b of the axle-boxes A B. Each axle-section is provided at both sides of the collars i i' with shoulders p p', that fit into the recesses or dust-guards d d'. The axle may be arranged with one or more collars, i i', at each end, and the axle-boxes 60 with a corresponding number of grooves, b b, or the collars and grooves may be entirely dispensed with, as desired. The wheels are rigidly attached to the axle and rotated therewith. 65

The coupling of the axle-section is shown in detail in Figs. 5, 6, and 7, and has for its object to permit the easy turning of either vehicle-wheel independently of the other when turning curves. For this purpose the axle-section k is provided with an inner tapering end, l, which fits into a socket, m, of corresponding size at the inner end of the outer axle-section, k'. The connection of the axle-sections is made by means of a ring-shaped 75 screw-nut, n, which screws into the interiorly-threaded end n' of the socket m. The enlarged annular head of the screw-nut n prevents it from entering too far into the socket m. The nut n is secured to the socket m by means of 80 one or more screws, r r', as shown in Figs. 6 and 7, whereby a reliable connection of the axle-sections k k' is obtained. The screw-nut n is further provided with a recess, o, by which the same is taken hold of in screwing in or 85 unscrewing the same.

The lubricating of the axle-sections within the coupling g is accomplished by an annular oil-duct, u, which is closed by a screw-plug, u'. Either the front or hind axle may be made of 90 one or two parts; but when they are made of two parts they are united by a suitable coupling and supported on two or more axle-boxes, as the case may be.

Having thus described my invention, I claim 95 as new and desire to secure by Letters Patent—

1. The combination of the parts A B, having journal-bearings a, recesses or dust-guards d d', and lubricating-chamber c, substantially as set forth.

2. The combination of the box parts A and B, having journal-bearings a and dust-guards

d d', with a rotating axle, *k k'*, having journals *h h'* and shoulders *p p'*, substantially as specified.

3. The combination of the parts A, B, having 5 journal-bearings *a*, an annular groove, *b*, and dust-guards *d d'*, with a rotating axle, *k k'*, having journals *h h'*, collars *i i'*, and shoulders *p p'*, substantially as specified.

In testimony whereof I have signed this specification in the presence of two subscribing witnesses.

LORENZ LEIRER.
